UNITED STATES PATENT OFFICE.

GIDEON PILLOW BROWN, OF CHICAGO, ILLINOIS.

WATER-TUBE SOOT-BLOWER.

1,198,185.

Specification of Letters Patent. Patented Sept. 12, 1916.

Application filed December 9, 1910. Serial No. 596,403.

To all whom it may concern:

Be it known that I, GIDEON PILLOW BROWN, a citizen of the United States of America, and resident of Chicago, Cook county, Illinois, have invented a certain new and useful Improvement in Water-Tube Soot-Blowers, of which the following is a specification.

My invention relates to soot blowers for water tube boilers.

It relates more particularly to blowers for this purpose that have a set of nozzles arranged to extend through the side of the furnace wall, and which are mounted to swing from side to side. These nozzles are arranged in line with the spaces between the tubes, so that the jets do not impinge directly against the side of the tubes, but simply pass in between the tubes. This mode of operation is all right for a boiler in which the tubes are horizontal, as in such case the back and forth swing of the nozzles does not cause the jets to cut across the tubes. In boilers, however, in which the tubes are inclined, as is often the case, the nozzles, operating in horizontal planes, swing obliquely across the tubes, which is objectionable. To get the best results, it has been found, the jets or blasts should always blow between the tubes, and never cut across the same.

The object of my invention is, therefore, to provide an arrangement whereby the nozzles of the blower, when disposed in position to swing about a vertical axis, or when disposed one above the other in vertical series, and when used in conjunction with a boiler in which the tubes are inclined, will keep the jets or blasts moving between the tubes, by causing the nozzles to follow the direction of the tube, thus preventing the same from cutting across the tubes, or at least greatly reducing the tendency in that direction, during the sweep of the nozzles from side to side, and in conjunction with a vertical supply pipe to which the nozzles are suitably connected.

It is also an object to provide an improved arrangement for withdrawing the nozzles from the furnace after the soot has been blown from the tubes.

It is also an object, of course, to provide an improved arrangement whereby the nozzles may swing in planes parallel with the inclined tubes, in conjunction with a furnace having a vertical opening in the side wall thereof, an opening of this kind being more

especially desirable in a brick wall, for in a wall of this kind an inclined opening has been found to be undesirable.

To these and other useful ends my invention relates to matters hereinafter set forth and claimed.

In the accompanying drawings Figure 1 is a side elevation of a soot blower for water tube boilers, showing one side of the furnace, and a number of the tubes, in section, and showing the nozzles pushed into the furnace to blow the soot off from the tubes. Fig. 2 is a front elevation of the structure shown in Fig. 1. Fig. 3 is a horizontal section on line 3—3 in Fig. 1. Fig. 4 is an enlarged detail sectional view of the swivel connection that permits the nozzle to move up and down and also swing sidewise about a vertical axis. Fig. 5 is an enlarged section on line 5—5 in Fig. 4.

As thus illustrated, the water tubes A are inclined and arranged in the usual and well-known manner. The wall or side B of the furnace has an opening C in which the plate D is disposed in a vertical position. The openings d in this plate are covered by the sliding cover plate d', which latter has small openings d² for the nozzles E that are mounted on the vertical pipe e. The springs e' are arranged on the nozzles between the pipe e and the plate d' to keep the latter pressed tightly against the plate D. The vertical supply pipe or header F has its upper end connected with the lower end of the pipe e by an elbow coupling f having a handle f' to swing the pipe e from side to side about a vertical axis coincident with the pipe F. This pipe F is supported by pins f² that engage in cam slots f³ in the sides of the nozzle base f⁴. These cam slots cause the pipe F to move up and down when oscillated or turned back and forth by the handle f'. In this way, and by moving the nozzles up and down while they move from side to side, they are caused to follow the slant or incline of the water tubes, so that the jets or blasts never cut across the tubes, or at least have less tendency to do so than in arrangements where the nozzles swing in horizontal planes. The angle of the cam slots f³ is such that the up and down motion is just sufficient to keep the nozzles always pointing between the tubes A. Thus the side sweep of the jets or blasts does not, at least not in the way they would if operated in horizontal planes, bring them against the

tubes, even in a boiler in which the tubes are inclined.

The air or steam for blowing is supplied from a pipe G and through the telescoping connection g to the swivel connection g'. The latter is so constructed that the rise and fall and the oscillation of the pipe F does not cut off the pressure. The connection g' permits the blower to be moved in and out, so that when the blowing operation is finished the nozzles can be withdrawn from the chamber. For this purpose the base f⁴ is mounted on tracks f⁵, and a hand lever H is connected by a link h with the swivel joint g', whereby the blower can be pushed into position and then pulled out. The slots f³ can have steps f⁶ to enable the operator to raise and lower the blower step by step, thus making the operation easy and convenient. A lever I may be provided for assisting in the control of the movement of the pipe e, if such is necessary.

Thus I provide a soot blower that can be operated in connection with a boiler in which the water tubes are inclined. The blower will work in a vertical position, and will always blow between the tubes, or at least have a greater tendency to do so, fully as well as in a boiler where the tubes are horizontal.

Obviously, the provisions or mechanism for causing the nozzles to follow the direction of the tubes may be of any suitable, known or approved character, and I do not, therefore, limit myself to the exact construction shown and described. My invention contemplates, broadly, a set of nozzles arranged one above the other in vertical series, each nozzle movable in a plane parallel with the inclined water tubes but oblique to the said vertical series arrangement of the nozzles.

My invention, it will be seen, has the great advantage that the nozzles swing in planes parallel with the water tubes, notwithstanding that the supply pipe or header is vertical, whereby the latter may be disposed in the vertical opening in the side wall of the boiler, and whereby, also, the blower may be mounted for withdrawal from the boiler when not in use.

It will be seen that the nozzles E are not only so connected together and arranged and operated that they are all on a vertical line when in normal or central position between the two sides of the vertical opening in the wall of the furnace, but are also constructed and arranged in such manner that the series of nozzles is exactly vertical during the operation of the blower, and for all positions of the nozzles. In other words, the nozzles are all arranged one above the other along a common vertical line, and this line is always vertical, regardless of the position of the nozzles. Thus, when the

nozzles are swung to one side, they will all encounter the side edge of the vertical opening at the same time, so that they all have the same degree of movement to either side of the center position. Also, the nozzles all move at the same speed, during the operation of the blower, because they are all of the same length and move about a common axis. It will also be seen that my invention avoids the necessity of making inclined openings in the side wall of the boiler. As is well known, an inclined opening is objectionable, especially when the wall is made of brick, and for this reason it has become desirable to use vertical openings. Thus, I provide a blower in which the nozzles will follow the general direction of the inclined water tubes, and which can be used with a boiler setting in which the side walls are provided with vertical openings for the different passes of the boiler, such, for example, as the ordinary and well-known Babcock & Wilcox boiler. This is all accomplished, it will be seen, with a blower structure in which the upright series of nozzles is always vertical, and in which the header may also be vertical if such is necessary or desirable.

What I claim as my invention is:—

1. In a soot blower for water tube boilers having inclined tubes, a set of nozzles for blowing between and crosswise of the tubes, means for swinging the nozzles from side to side, about an axis extending crosswise of said tubes, and means adapted to be operated without disturbing said axis for causing the nozzles to rise and fall as they swing back and forth.

2. In a soot blower for water tube boilers having inclined tubes, a set of nozzles, a vertical pipe to which the nozzles are attached, means for moving the pipe about a vertical axis, to swing the nozzles from side to side, and means adapted to be operated without disturbing said axis for raising and lowering said pipe as the nozzles move back and forth.

3. In a soot blower for water tube boilers having inclined tubes, a set of nozzles movable about a vertical axis, which axis is oblique to the said tubes, and means for causing the nozzles to follow the direction of the tubes.

4. In a soot blower, a set of nozzles for blowing between and crosswise of the tubes, and a telescoping feed pipe connection to permit the blower to be moved in and out, and means for swinging said nozzles from side to side.

5. In a soot blower for water tube boilers having inclined tubes, a set of nozzles for blowing between the tubes, means for swinging the nozzles from side to side, about a vertical axis, and automatic means for causing the nozzles to rise and fall, as they

swing back and forth, whereby said nozzles swing in planes oblique to the said axis.

6. In a soot blower for water tube boilers having inclined tubes, a set of nozzles, a vertical pipe to which the nozzles are attached, means for moving the pipe about a vertical axis, to swing the nozzles from side to side, and automatic means for raising and lowering said pipe as the nozzles move back and forth, whereby said nozzles swing in planes oblique to the said axis.

7. In a soot blower for water tube boilers having inclined tubes, a set of nozzles movable about a vertical axis, and automatic means for causing the nozzles to follow the direction of the tubes, whereby said nozzles swing in planes oblique to the said axis.

8. In a soot blower for water tube boilers having inclined tubes, a set of nozzles arranged one above the other in vertical series, and means for causing said nozzles to follow the direction of the tubes, whereby said nozzles swing in planes oblique to the said vertical series arrangement thereof.

25 9. In a soot blower for water tube boilers having inclined tubes, a set of nozzles arranged one above the other in vertical series, and means for causing said nozzles to follow the direction of the tubes, whereby said nozzles swing in planes oblique to the said vertical series arrangement thereof, there being a vertical supply pipe to which said nozzles are suitably connected.

10. In a soot blower for water tube boilers having inclined tubes, a set of nozzles arranged one above the other in vertical series, and means for causing said nozzles to follow the direction of the tubes, whereby said nozzles swing in planes oblique to the said vertical series arrangement thereof, there being a wall for inclosing said boiler having a vertical opening in the side thereof, and a vertical supply pipe disposed at said opening, suitably connected with said nozzles.

11. In a soot blower for water tube boilers having inclined tubes, a set of nozzles arranged one above the other in vertical series, and means for causing said nozzles to follow the direction of the tubes, whereby said nozzles swing in planes oblique to the said vertical series arrangement thereof, and means for moving the said nozzles toward and away from the boiler.

55 12. In a soot blower for water tube boilers having inclined tubes, a vertical header, a set of movable nozzles for said vertical header, arranged one above the other, and means for causing said nozzles to follow the direction of the tubes, whereby said nozzles swing in planes oblique to the said vertical header.

13. A soot-blower for water-tube boilers having inclined tubes, comprising a set of nozzles disposed one above the other in ver-

tical series, and means whereby said nozzles are movable back and forth in the direction of the tubes and having provisions for maintaining the said vertical position of said series during the operation of the blower, so that said series is vertical in every position of said nozzles, whereby the nozzles move in planes oblique to the said permanently vertical series arrangement thereof, said boiler having a side wall provided with a vertical opening for said nozzles.

14. In a soot-blower for water-tube boilers having inclined tubes, a set of oscillating nozzles disposed opposite the spaces between the tubes and arranged one above the other in vertical series, and means in the blower for compelling said nozzles to move in parallel inclined planes having the same general direction of the tubes, and for maintaining the said vertical position of said series at all times during the operation of the blower.

15. In a soot-blower for water-tube boilers having inclined tubes, a set of oscillating nozzles disposed opposite the spaces between the tubes and arranged along a common vertical line, and means independent of said tubes and forming part of the blower structure for causing said nozzles to oscillate in the general direction of the tubes and in planes oblique to said vertical line, and for maintaining the said vertical position of said series during the operation of the blower.

16. In a soot-blower for water-tube boilers having inclined tubes, a set of disposed nozzles opposite the spaces between the tubes and arranged one above the other in vertical series, and means for imparting back and forth movement to the nozzles in the general direction of the inclined tubes and having provisions for connecting together said nozzles and maintaining the said vertical position of said series for all positions of said nozzles during the operation of the blower.

17. In a soot-blower for water-tube boilers having inclined tubes, a set of nozzles arranged one above the other in permanently vertical series, and means forming part of the blower itself for causing said nozzles to follow the direction of the inclined tubes, whereby the nozzles move in planes oblique to the said vertical series arrangement thereof.

18. In a soot-blower for water-tube boilers having inclined tubes, a set of oscillating nozzles disposed opposite the spaces between the tubes and arranged one above the other in permanently vertical series, means in the blower itself for causing said nozzles to move in the general direction of the tubes, in planes inclined like the tubes, and means whereby said blower is movable toward and away from said tubes.

19. In a soot-blower for water-tube boilers having inclined tubes, a set of oscillating nozzles disposed opposite the spaces between the tubes and arranged along a common and 5 permanently vertical line, and means including a permanently vertical header for causing said nozzles to oscillate in planes which are inclined in the general direction of the tubes and oblique to said vertical line.
- 10 20. In a soot-blower for water-tube boilers having inclined tubes, a set of nozzles disposed opposite the spaces between the tubes and arranged one above the other in permanently vertical series, and means forming 15 part of the blower itself for imparting movement to the nozzles in planes which are inclined in the general direction of the tubes, said boiler having a side wall provided with a vertical opening for said 20 nozzles.
21. In a soot-blower for water-tube boilers having inclined tubes, a set of nozzles arranged one above the other in vertical series, means for causing said nozzles to 25 follow the direction of the inclined tubes,
- whereby the nozzles move in planes oblique to the said vertical series arrangement thereof, a wall having openings for said nozzles, and means including sliding plates operated by said nozzles for closing the said 30 openings to the admission of air.
22. In a soot-blower for water-tube boilers having inclined tubes, a set of oscillating nozzles disposed opposite the spaces between the tubes and arranged one above the other in vertical series, means for causing said nozzles to move in the general direction of the tubes, in planes which are inclined like the tubes, a wall having openings for said nozzles, and means including sliding plates operated by the nozzles for closing the said 35 openings to the admission of air and springs on the nozzle-shanks to hold said plates against said wall. 40

Signed by me at Chicago, Cook county, 45 Illinois, this 3rd day of Dec., 1910.
